UNITED STATES PATENT OFFICE.

JOSEPH VAN ACKEREN, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

INCLINED COKING RETORT OVEN.

Application filed September 29, 1921. Serial No. 504,142.

To all whom it may concern:

Be it known that I, JOSEPH VAN ACKEREN, a citizen of the United States, residing in Pittsburgh, in the county of Allegheny and State of Pennsylvania, have invented a new and useful Improvement in Inclined Coking Retort Ovens, of which the following is a specification.

This invention comprehends improvements in the art of inclined coking retort ovens, and has for objects the provision of an inclined retort that is highly efficient in operation and which will produce high grade coke and effect a substantially complete by-product recovery, although the entire distilling operation is conducted rapidly and with great conservation and equality in distribution of the heat.

Important characteristics of the invention are: the employment of the combination oven principle in an inclined coking retort oven construction, whereby the heat for coking the charges of coal in the retorts or coking chambers may be developed from the combustion of gas of distillation of the coal coked in such retorts, or alternatively, from a special generator gas such as producer gas, in order to conserve the entire product of the relatively richer coke oven gas; the provision of a system of combustion in the flame or combustion flues of the heating walls of the retort chambers, and of flow through the regenerators, by which system the flow from individual regenerators and flues may be regulated by means that is readily accessible to the operator of the retort battery; the attainment of equality in distribution of the heating effect in the heating walls with the employment of the extraneously derived gas, such as producer gas, for fuel; and, as a further feature of the invention, the provision of expansion joints extending crosswise of the battery, permitting such expansion to occur as is necessary to maintain the entire structure in proper alignment, and yet locating such expansion joints so that they by-pass the regenerators that are employed for delivering fuel gas to the flues, which the result that leakage from the fuel gas regenerators into the inflow air regenerators or the outflow regenerators is avoided.

In addition to the general objects recited above, the invention has for further objects such other improvements or advantages in

construction and operation as are found to obtain in the structures and devices which will now be described and claimed.

In the accompanying drawings, forming a part of this specification and showing, for purposes of exemplification, a preferred form and manner in which the invention may be embodied and practiced, but without limiting the claimed invention specifically to such specific instance or instances:

Figure 1 is a vertical sectional elevation of an inclined retort construction embodying features above specified and constructed in accordance with the improvements of the present invention, the view being taken crosswise through a heating wall and the regenerators in a vertical plane indicated by the line A—A of Fig. 2;

Fig. 2 is a composite vertical sectional elevation taken longitudinally of a battery of inclined retorts, in planes indicated by the lines C—C and D—D of Fig. 1;

Fig. 3 is another crosswise section of the retort battery, the view being taken through a retort in a plane indicated by the line B—B of Fig. 2; and

Fig. 4 is a composite horizontal elevation and sectional view of the retort battery, the view being taken on the several planes indicated by the lines F—F, G—G, H—H and M—M of Fig. 1.

The same characters of reference designate the same parts in each of the several views of the drawings.

In its present embodiment, the invention is incorporated in a combination inclined coking retort oven designed for the employment of either the coke oven gas, or alternatively for the employment of an extraneously derived gas, such as producer gas, for the heating fuel. For convenience, the present description will be confined to this use of the invention; features of construction and operation are however capable of other valuable applications such as in an inclined retort oven construction designed solely for the employment of the extraneously derived gas as fuel; consequently the scope of the invention is not confined to the specific use and specific embodiment herein described as an illustrative example.

Referring to the drawings: There are illustrated views of an inclined retort oven of the by-product type, as herein above mentioned, which retort embodies in its con-

struction a plurality of intermediate vertically elongated inclined retorts or coking chambers 12, 12, said coking chambers inclining downwardly from the charging and 5 distillate out-flow end to the discharge end, as shown in Fig. 3. The inclined heating walls 11 form the side walls of the respective coking chambers 12, as shown more 10 particularly in Fig. 2. Together with the regenerators hereinafter mentioned, the heating walls 11, and coking chambers 12 are supported by the heavy supporting walls 13, 13, that rest on the mat 14 of the battery and are spaced, as shown in Fig. 2, 15 to provide intermediate tunnels 15 that afford access to the flow-regulating means of the several regenerators, as will hereinafter appear.

The coal to be coked is charged into the 20 retorts 12 through charging holes 16 located in the top of the retort battery and at the upper ends of the several retort chambers, and the finished coke is discharged through the door openings 17 that are located at the bottom of the several inclined 25 retorts 12. The inclination of the retorts 12 is substantially that of the angle of repose of the coal charged into said retorts and, when the doors are removed from the 30 discharge openings 17 the finished coke will slide by gravity out of the retorts 12. During the coking or distilling operation, the holes 16 of the respective retorts are employed as distillate outlets, and, in order 35 to conserve the above distillate and gases, said holes 16 are, throughout the distilling operation, communicably connected with any suitable type of gas off-take main. Adjacent to each combined charging and 40 distillate outlet 16, there is provided in the top of each retort 12, a smoke hole 18, which is closed by any suitable cover during the distilling operation, but preferably opened during the charging operation, to allow the 45 escape of smoke which arises as the coal is charged into the hot retort.

Heat for coking the charges of coal into the several retort chambers 12 is derived from the heating walls 11 above mentioned. 50 Referring now more particularly to Fig. 1, each heating wall 11 is constituted of a plurality of vertical combustion flues 19 that are operatively disposed into pairs K, each such pair being constituted of a lower flue 55 L of relatively lesser height and an upper flue U of relatively greater height. The flues of each pair K are communicably connected at their upper ends by a passageway 20 permitting the combustion products from 60 one flue, which is operating for inflow, to pass inwardly and down through the other flue, which is operating for outflow, of the same pair. The flues U of alternate pairs 65 and the flues L of intermediate pairs operate 70 concurrently for flow in the same direction,

while the flues L of alternate pairs and the flues U of intermediate pairs are operating concurrently for flow in the opposite direction. Reversal of the retort battery, at the 75 end of an operating period, determined by practice, is effective to cause the several upflow or burning flues to become downflow flues and concurrently to cause the several downflow flues to become upflow flues.

The regenerators 21 are incorporated in 75 the inclined refractory structure 22 that is located beneath the retorts 12 and the heating walls 11. Each regenerator 21 is a chamber containing open brickwork, commonly called checkerwork, and indicated at 80 23, with a duct 24 underneath said checkerwork. As shown in Fig. 1 the regenerators corresponding to each heating wall 11 are, of course, disposed at different levels or tiers, and each series of regenerators that 85 extends longitudinally of the battery along the same tier is communicably connected by means of the ducts 24 individual to the regenerators with a channel 25 extending longitudinally of the retort battery and constituting a flow means through which a 90 gaseous medium is introduced into the several regenerators with which said channel is communicably connected, or exhausted from the regenerators when the latter are 95 operating for outflow. The several regenerators are heated, in alternation, by the hot combustion products that are exhausted from the flame or combustion flues hereinbefore mentioned and then impart such 100 heat to the medium that they feed into these flame flues.

In accordance with the invention, the series of regenerators corresponding to each heating wall is disposed into groups N of 105 alternate pairs of regenerators and groups O of intermediate pairs of regenerators. With the exception of the extreme upper and lower pairs of regenerators of the series, each regenerator 21 is communicably connected by 110 means of ducts 26 with two adjacent flame flues, the ducts 26 of the respective regenerators 21 leading however to flame flues of different adjacent pairs K, as shown in Fig. 1. The ducts 26, however, may lead from individual portions of a regenerator, separated by the partition 33, as shown in Fig. 2. The extreme upper and lower pairs of regenerators are each connected by a duct 27 with the extreme upper and lower flame flues of 115 the corresponding heating wall. With this construction, each flame flue 19 of each heating wall is communicably connected by a duct system with a pair of adjacent separate regenerators, the flow through the communicably connected regenerators being maintained concurrently in the same direction as the flow through the flues.

In the present embodiment of the invention, one member of each pair of flame flues 120

- K is burning, while the other member of each pair of said flame flues is operating for downflow to convey waste products to the regenerators beneath. The reversal in flow 5 through the flame flues 19 and their communicably connected regenerators is effected at the end of an operating period, determined by practice, and by means of any preferred type of reversing mechanism. The 10 function of such reversal is as follows: The regenerators that prior to the reversal operated as inflow regenerators become outflow regenerators, and the outflow regenerators become inflow operating regenerators. 15 The upburning flues switch function with the downflow operating flues and the supply of gas is turned off from the previously upburning flues and turned on into the inlets of the previously downflow operating flues. 20 The tops of the respective flues 19 may be reached by access flues 28 extended vertically through the top of the battery construction, there being an access flue positioned over each flame flue of each heating wall. 25 In order to permit the alternative employment of coke oven gas as the fuel, a vertical coke oven gas supply duct 29 extends through the top of the battery construction over each channel 20 of each heating wall. 30 When the battery is employing coke oven gas, the ducts 29 feed the coke oven gas to the flues 19 that are operating for downflow, and the air to support combustion is supplied by the upflow-operating flues 19 that 35 communicate by the channels 20 with said downflow operating flues. The supply of coke oven gas is derived from supply-devices, such as the gas guns 40 which enter the inlets of the respective ducts 29 and are 40 communicably connected with a suitable coke-oven gas main 41 suitably supported over the top of each heating wall.
- A special feature of the invention resides in the individual connections 24 of the several regenerators of each tier to the flow channel 25 corresponding to that tier. As shown in Fig. 1, each such duct connection 24 is in substantial registry with an inspection hole 30 corresponding to each individual 45 duct connection. The flow through the individual regenerators may thus be regulated by means of the usual movable dampers or slide bricks 31 located in the several flow channels 25 adjacent to the points of communication of the ducts 24 with said flow channels. The inspection holes 30 may be 50 reached conveniently by an operator stationed in a tunnel 15 and a rod may be inserted through the inspection hole corresponding to any individual regenerator for the purpose of regulating the flow between the regenerator and the channel 25, independently of the flow between the other regenerators and said channel. 55 The operation of the inclined retort bat-
- tery, assuming that there is employed a special generator gas, such as ordinary producer gas, as the fuel, is as follows: A supply of producer gas is permitted to flow through the corresponding flow channel 25 into one 70 regenerator P of the inflow operating pairs, such as pairs N. Passing through said regenerators, the producer gas is preheated before being delivered into the burning flame flues. During the inflow of producer gas 75 into said regenerators P, air flows into the regenerators A of said inflow operating pairs N and passing through said regenerators is preheated prior to its delivery into the burning flame flues. In the flame flues, which are 80 communicably connected by the channels 20 to the burning flame flues, downflow is maintained, said downflow operating flame flues receiving the waste products from the burning flame flues and delivering such waste 85 products to the regenerators that are operating as outflow regenerators W. On reversal of the flow, the inflow operating regenerators and flues become outflow regenerators and flues and concurrently outflow regenerators and flues become inflow regenerators and flues. 90
- In operating the battery with coke oven gas, the supply of producer gas to the inflow regenerators P is shut off and air is 95 permitted to flow into such regenerators in place of the producer gas. During coke oven gas operation, a supply of coke oven gas is maintained in the ducts 29 which feed such gas to be burned downwardly in the 100 downflow flues. The reversing mechanism is operated at each reversal to place all of the inflow operating regenerators in communication with the air supply, and concurrently all of the outflow regenerators in 105 communication with the exhaust. 110
- Alternatively, during such coke oven gas operation, some of the inflow-operating regenerators, such as the regenerators P may be employed for conveying to the upflow flues a neutral gaseous diluent, such as return waste gas, which mixes in said flues with the air supplied by the inflow regenerators A and has the effect of lengthening 115 the flames in the downflow burning flues, thereby preventing flame concentration in the upper region of the heating walls and effecting other advantageous results fully set forth in the co-pending application of Joseph Becker for Letters Patent of the United States, for a coking retort oven, filed April 23, 1920, Serial No. 376,126. 120
- A further feature of the invention resides in the novel expansion joint construction. As shown in Figs. 2 and 4, the expansion joints 32 are disposed in vertical planes crosswise of the battery and extend between regenerators which only operate for the flow of air or waste heat. The expansion joints 125 are located entirely remote from those re-
- 130

- generators which on inflow operate for producer gas, with the result that leakage from or into the producer gas regenerators is avoided. These expansion joints permit expansion longitudinally of the battery without any substantial danger of leakage developing in the structure and particularly in those regenerators which are employed for the producer gas.
19. The invention as hereinabove set forth is embodied in a particular form of construction, but may be variously embodied within the scope of the claims hereinafter made.
- What I claim is:
1. In an inclined retort battery, in combination: a plurality of inclined retort chambers; heating walls contiguous to said retort chambers and respectively constituted of vertical combustion flues, the flues of each heating wall being grouped into pairs with one member of each pair communicably connected with the other member of the same pair; regenerators disposed in tiers at a lower level than said combustion flues and grouped into crosswise series corresponding to the respective heating walls, each combustion flue being communicably connected with a pair of such regenerators, and each pair of the thus connected regenerators, when operating for inflow, being constituted of an air regenerator and a regenerator for feeding fuel gas; substantially as specified.
2. In an inclined retort battery, in combination: a plurality of inclined retort chambers; heating walls contiguous to such retort chambers and respectively constituted of vertical combustion flues; regenerators disposed in tiers at a lower level than said combustion flues and grouped into crosswise series corresponding to the respective heating walls and communicably connected with said combustion flues; flow channels extending longitudinally of the battery and individually corresponding with the respective tiers of regenerators, each flow channel being communicably connected by separate duct means with the individual regenerators of its respective tier; and regulable damper means individual to the duct means connecting individual regenerators with such flow channels; substantially as specified.
3. In an inclined retort battery, in combination; a plurality of inclined retort chambers; heating walls contiguous to such retort chambers and respectively constituted of vertical combustion flues, the flues of
- each heating wall being grouped into pairs with one member of each pair communicably connected with the other member of the same pair; regenerators disposed in tiers at a lower level than said combustion flues and grouped into crosswise series corresponding to the respective heating walls, each combustion flue being communicably connected with a pair of such regenerators; and means for effecting individual control of flow through individual regenerators; substantially as specified.
4. An inclined retort battery having a plurality of inclined retort chambers, and heating walls contiguous to said retort chambers and respectively constituted of vertical combustion flues, the flues of each heating wall being grouped into pairs with one member of each pair communicably connected with the other member of the same pair, combined with regenerators disposed in tiers at a lower level than said combustion flues and grouped into crosswise series corresponding to the respective heating walls, each combustion flue being communicably connected with a pair of such regenerators, and each pair of the thus connected regenerators, when operating for inflow, being constituted of an air regenerator and a regenerator for feeding fuel gas; substantially as specified.
5. An inclined retort battery having a plurality of inclined retort chambers, and heating walls contiguous to said retort chambers and respectively constituted of vertical combustion flues, the flues of each heating wall being grouped into pairs with one member of each pair communicably connected with the other member of the same pair, combined with regenerators disposed in tiers at a lower level than said combustion flues and grouped into crosswise series corresponding to the respective heating walls, each combustion flue being communicably connected with a pair of such regenerators; substantially as specified.
6. An inclined retort battery having a plurality of inclined retort chambers, flued heating walls contiguous to said retort chambers, and crosswise regenerators directly communicably connected with said heating walls, combined with regulable means for effecting individual control of the flow through individual regenerators; substantially as specified.
7. An inclined retort battery having a plurality of crosswise inclined retort chambers, crosswise heating walls contiguous to said retort chambers, and regenerators disposed in tiers at a lower level than said heating walls and grouped into crosswise series corresponding to the respective heating walls, combined with flow channels extending longitudinally of the battery and individually corresponding with the respec-

five tiers of regenerators, each flow channel being communicably connected by separate duct means with the individual regenerators of its respective tier, and regulable damper means individual to the duct means connecting individual regenerators with such flow channels; substantially as specified.

8. In an inclined retort battery having a plurality of retort chambers, and heating walls contiguous to such retort chambers, combined with the improvement characterized by regenerators disposed in series corresponding to the respective heating walls, longitudinal channels interconnecting said regenerators, and means for regulating the flow between individual regenerators and said longitudinal channels; substantially as specified.

9. In an inclined retort battery having a plurality of inclined retort chambers, and fluid heating walls contiguous to said retort chambers, combined with the improvement characterized by crosswise regenerators disposed in series individual to each heating wall, and means for effecting individual regulation of the flow through individual regenerators; substantially as specified.

10. In an inclined retort battery having a plurality of retort chambers, and heating walls contiguous to said retort chambers, combined with the improvement characterized by regenerators disposed in tiers and grouped into crosswise series corresponding to the respective heating walls, a common flow channel for all the regenerators of each tier, and means for effecting individual regulation of the flow through individual regenerators; substantially as specified.

40 11. In an inclined retort battery having a plurality of crosswise inclined retort chambers, and crosswise heating walls contiguous to said retort chambers, combined with the improvement characterized by regenerators disposed in series corresponding to the respective heating walls, flow channels interconnecting said regenerators longitudinally of the battery, and means for effecting individual regulation of the flow in individual regenerators; substantially as specified.

12. In an inclined retort battery, in combination: a plurality of inclined retort chambers; heating walls contiguous to said retort chambers; regenerators disposed in series corresponding to the respective heating walls and constituted of air, fuel gas, and waste heat regenerators, and crosswise expansion joints extended only between the air and waste heat regenerators and by-

passing the aforesaid fuel gas regenerators, 60 whereby leakages of the fuel gas are avoided; substantially as specified.

13. An inclined retort battery having a plurality of inclined retort chambers, heating walls contiguous to said retort chambers, and regenerators communicably connected with said heating walls and constituted of air, fuel gas, and waste heat regenerators, combined with expansion joints extended only between air and waste heat regenerators and by-passing the fuel gas regenerators, whereby leakages of the fuel gas are avoided, substantially as specified.

14. An inclined retort battery having a plurality of inclined retort chambers, heating walls contiguous to said retort chambers, and regenerators communicably connected with said heating walls and constituted of air, fuel gas, and waste heat regenerators, combined with expansion joints extended 70 crosswise of the battery and located in the structure so as to by-pass the aforesaid fuel gas regenerators, whereby leakages of fuel gas are avoided; substantially as specified.

15. In an inclined retort battery, in combination: a plurality of inclined retort chambers; heating walls contiguous to such retort chambers and respectively constituted of vertical combustion flues, the flues of each heating wall being grouped into pairs with one member of each pair communicably connected with the other member of the same pair; regenerators disposed in tiers at a lower level than said combustion flues and grouped into crosswise series corresponding to the respective heating walls, said regenerators being communicably connected with said combustion flues; and fuel gas supply connections communicably connected with the upper ends of the respective pairs of combustion flues; substantially as specified.

16. In an inclined retort battery having a plurality of retort chambers, and heating walls contiguous to such retort chambers, combined with the improvement characterized by inflow and outflow regenerators communicably connected with the respective heating walls, the inflow regenerators being jointly operable for conveying air to the said heating walls or separately operable for conveying air and an extraneously derived gas, and supply connections for feeding fuel gas to the upper portion of said heating walls; substantially as specified.

In testimony whereof I hereunto affix my signature, this 24th day of September, 1921.

JOSEPH VAN ACKEREN.
